UNITED STATES PATENT OFFICE.

WILLIAM CASE, OF CHICAGO, ILLINOIS, ASSIGNOR TO THE NATIONAL MALLEABLE CASTINGS COMPANY, OF CLEVELAND, OHIO.

DESIGN FOR A BOLSTER FOR CARS.

SPECIFICATION forming part of Design No. 25,671, dated June 23, 1896.

Application filed May 12, 1896. Serial No. 591,301. Term of patent 14 years.

To all whom it may concern:

Be it known that I, WILLIAM CASE, of Chicago, in the county of Cook and State of Illinois, have invented a new and original Design 5 for Car-Bolsters, of which the following is a full, clear, and exact description.

The invention is illustrated in the accompanying drawings, in which—

Figure 1 is a perspective view of a car-bolster embodying my design. Fig. 2 is a bottom plan view thereof.

My design consists in a car-bolster, having substantially the form shown in the accompanying drawings and herein described.

15 The car-bolster 2 is hollow, substantially

rectangular in cross-section, having end portions 3 of substantially uniform cross-section throughout, with a middle portion 4 of greater depth. The surface of the bolster is substantially flat from end to end. 20

I claim—

The design for car-bolsters substantially as herein shown and described.

In testimony whereof I have hereunto set my hand.

WILLIAM CASE.
